(57) CLAIM

The ornamental design for a ladies underwear, as shown and described.

DESCRIPTION

FIG. 1 is a front perspective view of a ladies underwear showing my new design;

FIG. 2 is a front elevation view thereof;

FIG. 3 is a rear elevation view thereof;

FIG. 4 is a left side elevation view thereof, the right side elevation view being a mirror image thereof;

FIG. 5 is a top plan view thereof;

FIG. 6 is a bottom plan view thereof;

FIG. 7 is a perspective view thereof, showing one side unattached; and,

FIG. 8 is another perspective view thereof, showing both sides unattached.

The broken lines shown in the drawings illustrate portions of the ladies underwear that form no part of the claimed design.
